CABLE HANGER

John F. Tucker, West Haven, Conn., assignor to
West Haven Buckle Company, West Haven,
Conn., a corporation

Application February 1, 1935, Serial No. 4,502

1 Claim. (Cl. 248—61)

This invention relates to an improvement in cable hangers, and while particularly adapted for supporting feed-wires, is applicable for supporting other devices and is an improvement on the device shown and described in Patent No. 5 705,391, dated July 22, 1902.

The device shown in this patent consisted of a U-shaped hook-member, over which a loop was passed and around which a strap was turned, 10 so as to be gripped between the loop and the hook-member.

The object of this invention is to add to the holding qualities of the patented device by the addition of a second loop, and the invention consists in the construction as hereinafter described and particularly recited in the claim.

In the accompanying drawing:

Fig. 1 is a perspective front view of a cable hanger constructed in accordance with my invention;

Fig. 2 is a perspective rear view of the same; and

Fig. 3 is a vertical sectional view.

In carrying out my invention, I employ a hook-member 5 formed from a single piece of metal bent into U-shape to form a bar 6, which is forwardly offset, and the ends 7 and 8 hooked to engage with a supporting-wire 9 or other device.

30 A strap 10 of strip-metal or other suitable material has one end 11 folded over the bars 12

and 13 of a loop-member 14, through which loop the ends of the hook-member extend. The other end 15 of the strap is passed around a cable or device to be supported and through a supplemental loop-member 16, thence over the bars 12 and 13 of the first loop-member, and the metal folded around them and beneath the bar 6 of the hook, so that when strain is applied, the bar 6 of the hook is crowded against the bar 13 of the loop, so as to compress the two reaches of metal between them. At the same time the upper bar 17 of the supplemental loop 16 is crowded against the bar 12 of the first loop, so as to grip the two reaches of metal passing between them, thus forming two gripping points instead of one, as in the previous construction.

The addition of a second loop adds but little to the cost, but doubles the gripping capacity of the device and adds to the assurance against slipping of the supporting-strap.

I claim:

A hanger comprising a hook-member having a forwardly-offset bar and two loop-members through which the hook-member extends, combined with a strap folded around the loop adjacent the offset bar and then passed through the second loop and over the first specified loop, whereby when strain is applied, the strap will be gripped between both bars of the first loop.
